The ornamental design for a grinding wheel shank, as shown and described.

DESCRIPTION

FIG. 1 is the perspective view of a grinding wheel shank of the invention;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof;

FIG. 8 is a cross-sectional perspective front view of the grinding wheel shank, taken along line 8—8 of FIG. 2;

FIG. 9 is a cross-sectional perspective front view of the grinding wheel shank, taken along line 9—9 of FIG. 2;

FIG. 10 is a rear perspective view; and,

FIG. 11 is a front view of the grinding wheel shank of the invention showing a plurality of diamond grinding tips rendered in broken line attached thereto.

Parts of the design shown in broken line are included to illustrate the design environment and form no part of the claimed design.
